(57) CLAIM

The ornamental design for a clothing support article, as shown and described.

DESCRIPTION

FIG. 1 is a front perspective of a clothing support article showing our new design;

FIG. 2 is a top plan view thereof;

FIG. 3 is a bottom plan view thereof;

FIG. 4 is a left side view thereof;

FIG. 5 is right side view thereof;

FIG. 6 is a top-down view thereof;

FIG. 7 is a bottom-up view thereof; and,

FIG. 8 is an enlarged front elevation view taken from FIG. 2.

The broken lines shown in FIG. 2 are included for the purpose of identifying the enlarged view shown FIG. 8 and form no part of the claimed design.
